(57) **CLAIM**

I claim the ornamental design for a bullseye ashtray, substantially as shown and described.

DESCRIPTION

FIG. 1 is a top plan view of a bullseye ashtray showing my new design;

FIG. 2 is a perspective view thereof; and,

FIG. 3 is a side elevation view thereof, all sides being identical.

1 Claim, 3 Drawing Sheets

FIG. 1

FIG. 2

FIG. 3
